United States Patent Office.

ANSON SEARLS, OF SAN FRANCISCO, CALIFORNIA.

Letters Patent No. 70,628, dated November 5, 1867.

IMPROVEMENT IN ADJUSTABLE PROP-JOINT FOR CARRIAGES.

The Schedule referred to in these Letters Patent and making part of the same.

TO WHOM THESE PRESENTS SHALL COME:

Be it known that I, ANSON SEARLS, of the city and county of San Francisco, State of California, have made a new and useful Improvement in Making Prop-Joints for Carriage-Tops, which I call the Adjustable Prop-Joint, of which the following specifications and accompanying drawings are an exact and clear description.

Adjustable Prop-Joint.

The nature and purpose of my invention consist in constructing prop-joints for carriage-tops of malleable iron or other metals, with a socket-pivoted joint, in place of the old-style stump-joint, which I call the centre-joint. Each side of this joint I construct a joint suitable for extending or shortening either end to the desired length. I call this the extension-joint.

By the use of the centre-joint I propose to reduce the cost, increase the strength, dispense with the old-style rivet, and add to the beauty and finish of the same. By the extension-joint I propose to make the prop-joint adjustable to the desired length, thereby dispensing with the usual expensive and troublesome mode of measuring each top and piecing out the stump-joint for each particular place.

For the purpose of extending or shortening, sliding joints with or without ratchets may be used, with set-screws or thimble-screws over the same. To accomplish this purpose, I adopt a socket screw-joint, as shown in Figures 1 and 2.

A is a section of the joint passing through a socket, C, and screwing into the section B at D. By turning the section A it will screw out or into the socket C, lengthening or shortening the joint at pleasure. The socket serves to strengthen the joint and cover all appearance of the screw.

The socket may be made loose, to slip on or off at pleasure, oval, square, or any other form. Prop-joints with this improvement may be made curved or straight. They also may be placed inside and close to the bows, from front to back bow, and from the back bow to the rail, and the top, falling on the top of the joint, dispenses with the prop-block, preventing the breaking of the bow by falling across the block.

Figure 2 is a sectional view.

Figure 3 is an isometrical view of the centre-joint.

E is the socket; F is the journal, fitting into the same; I is the pivot, passing through the journal F in section G, fastening the joint together.

Claim.

1. An adjustable or extension prop-joint.
2. A socket, pivoted, or centre-joint, all substantially as described and for the purposes set forth.

San Francisco, California, June 27, 1867.

ANSON SEARLS.
